DESIGN FOR A STRAP FOR HOLDING RIDING SPURS TO A BOOT

Roy W. Nelson, Cupertino, Calif.

Application February 14, 1949, Serial No. 848

Term of patent 14 years

(Cl. D38—16)

To all whom it may concern:

Be it known that I, Roy W. Nelson, a citizen of the United States of America, residing at Cupertino, in the county of Santa Clara and State of California, have invented a new, original, and ornamental Design for a Strap for Holding Riding Spurs to a Boot, of which the following is a specification, reference being made to the accompanying drawings, forming a part thereof.

Fig. 1 is a plan view in a spread-out position of a strap for holding riding spurs to a boot, showing my new design;

Fig. 2 is a perspective view of the same in a folded position.

I claim:

The ornamental design for a strap for holding riding spurs to a boot, substantially as shown.

ROY W. NELSON.
